UNITED STATES PATENT OFFICE

172,333

NOTE PAPER HOLDER

Louis L. Bresler, Hammond, Ind.

Application March 17, 1953, Serial No. 24,057

Term of patent 14 years

(Cl. D74—1)

To all whom it may concern:

Be it known that I, Louis L. Bresler, a citizen of the United States, residing at Hammond, in the county of Lake and State of Indiana, have invented a new, original, and ornamental Design for a Note Paper Holder, of which the following is a specification, reference being had to the accompanying drawing forming a part hereof.

Fig. 1 is a top plan view of a note paper holder, showing my new design;

Fig. 2 is a side elevational view thereof;

Fig. 3 is a front end elevational view thereof; and

Fig. 4 is a rear end elevational view thereof.

I claim:

The ornamental design for a note paper holder, substantially as shown.
